CLOSURE FOR A FOOD PACKAGE
OR THE LIKE

Henry H. Huston, Huntington, N.Y., assignor to Lily-Tulip Cup Corporation, New York, N.Y., a corporation of Delaware

Filed July 21, 1967, Ser. No. 7,918

Term of patent 14 years

(Cl. D58—26)

FIG. 1

FIG. 4

FIG. 2

FIG. 5

FIGURE 1 is a top view of a closure for a food package or the like showing my new design;

I claim:

The ornamental design for closure for a food package or the like, substantially as shown.
